Primary Examiner — Rhea Shields

(57) **CLAIM**

The ornamental design for a buoyant object for wave power generator, as shown and described.

DESCRIPTION

1. Buoyant object for wave power generator
- 1.1 : Perspective
- 1.2 : Front
- 1.3 : Top
- 1.4 : Bottom
- 1.5 : Cross-sectional
- 1.6 : Exploded

1 Claim, 6 Drawing Sheets1.1
